Primary Examiner — Rebekah A Caruso(74) *Attorney, Agent, or Firm* — Schwabe Williamson & Wyatt(57) **CLAIM**

We claim the ornamental design for a joystick button panel, as shown and described.

DESCRIPTION

FIG. 1 is a perspective view showing the design;

FIG. 2 is a front view;

FIG. 3 is a left side view;

FIG. 4 is a right side view; and

FIG. 5 is a top view; and,

FIG. 6 is a close-up perspective view of the design, enlarged and isolated for clarity of disclosure.

As the design will not be visible from the bottom or rear in use, no bottom or rear view has been provided. The dashed lines depict portions of the article and environmental structure that forms no part of the claimed design.
